(57) **CLAIM**

The ornamental design for a body pillow and pillowcase, as shown and described.

DESCRIPTION

FIG. 1 is a perspective view of a body pillow and pillowcase, showing our new design;

FIG. 2 is a perspective view thereof;

FIG. 3 is a top plan view thereof;

FIG. 4 is a front elevational view thereof;

FIG. 5 is a right side elevational view, the left side being a mirror image thereof;

FIG. 6 is a rear elevational view thereof;

FIG. 7 is a bottom plan view thereof;

FIG. 8 is a perspective view showing a second embodiment of the pillowcase;

FIG. 9 is a top plan view thereof;

FIG. 10 is a front elevational view thereof;

FIG. 11 is a right side elevational view, the left side being a mirror image thereof;

FIG. 12 is a rear elevational view thereof;

FIG. 13 is a bottom plan view thereof;

FIG. 14 is a perspective view showing a third embodiment of the pillowcase;

FIG. 15 is a top plan view thereof;

FIG. 16 is a front elevational view thereof;

FIG. 17 is a right side elevational view, the left side being a mirror image thereof;

FIG. 18 is a rear elevational view thereof; and,

FIG. 19 is a bottom plan view thereof.

The broken lines showing the human are for environmental purposes only and form no part of the claimed design.
